FUSIBLE COUPLING FOR FIRE ALARM
CIRCUITS

Glen D. Stauffer, Nappanee, Ind.

Application November 27, 1935, Serial No. 51,907

2 Claims. (Cl. 200—142)

The present invention relates to a new and improved fusible coupling and is especially adapted for an electric fire alarm system of the closed circuit type.

5 It is the primary object of this invention to provide a coupling constructed of non-conductive, combustible material that shall be inexpensive in construction and reliable in operation.

It is a further object to provide a coupling that 10 is easily assembled and adapted to be positioned within the conductor or line circuit, and will operate to break the circuit as soon as heat of a predetermined temperature is applied thereto.

With these and other objects in view, this invention 15 consists of certain novel features of construction, combination and arrangement of parts to be hereinafter more fully described and explained.

For a complete understanding of the invention, 20 reference is to be had to the following description and accompanying drawing, in which:

Figure 1 is a top plan view of the invention in use in a system of the closed circuit type.

Figure 2 is a side elevation view thereof.

25 Figure 3 is a partial sectional view disclosing the coupling, and the terminals in longitudinal cross section.

Figure 4 is a longitudinal sectional view through the coupling.

30 Figure 5 is a fragmentary view of the coupling and one terminal, and

Figure 6 is a sectional view of a modified coupling illustrating a pair of pins for insulating purposes.

35 Referring in detail to the drawing, the numeral 10 indicates the body of the coupling which may be constructed of a non-conductive, combustible material, such as fibre and bakelite and is preferably relatively thick and of flat ring or washer 40 shape in configuration. At diametrically opposite sides of the body 10, are provided a pair of threaded openings 11 and 12, adapted to receive the terminals 13 and 14 having reduced ends 15 and 16.

45 Referring to Figure 4, it is to be noted that the terminals are screw-threadedly engaged in the coupling 10 and may be adjusted so that the reduced ends 15 and 16 are maintained in spaced relation a predetermined distance. This is made 50 possible due to the adjustability of the terminals 13 and 14.

The terminals 13 and 14 are further provided with bores or recesses 17 and 18, for receiving the conducting wires 19 of the line circuit.

55 In order to maintain a proper contact, the

wires 19 are sealed within the recesses 17 and 18, with any suitable sealing means, but it is preferred that said sealing element be of a character readily fusible and of a low melting point. In Figure 4, the wire is shown as sealed at 20 within 5 the recess and at 21 at the point of the entrance of the wire within the recess.

The coupling may be insulated as illustrated in the modified form of Figure 6 in the event, it becomes necessary to lay the same upon or adjacent to a flat surface, as shown and for accomplishing this purpose, it is desired to provide a pair of recesses 22 extending transversely through the body and opposite points, the recesses receiving a pair of pins or posts 23 which are of insulating material. It is to be understood that the use of the insulating pins 23 is optional, but they should be of sufficient length or thickness to separate or elevate the coupling from contact with any foreign conductor.

20 In the use of the invention, one or more of the improved fusible couplings may be positioned at desired points in the system. After the terminals are properly adjusted so that the contact points 15 and 16 are spaced a predetermined distance, 25 solder or other fusible element 24 of a low melting point is poured within the opening 25, encasing and bridging the two terminals 15 and 16, thus converting the coupling into a conductor of electricity.

30 As above indicated, the hollow end of the terminals 13 and 14 permit the insertion and soldering of the line wires which form a part of the circuit.

35 In operation, when heat of a predetermined temperature is created, the fusible material 24 will melt, thus breaking the contact with the two terminals and converting the coupling to a non-conductor, thereby breaking the circuit.

40 Heat and flame will also destroy the body 10, thereby giving added assurance of the operation of the system.

45 It is also to be considered that the system is rendered additionally operative due to the fact that the wires encased within the hollow end of the terminal are surrounded by a fusible element of a low melting point, such as solder, thus making installation easier under certain conditions. Again, by employing the pins or posts 23, the 50 coupling is elevated above a flat surface, as shown in Figure 6, so as to facilitate the melting or removal of the plug or fusible material 24, as will be apparent.

While the invention is shown in use with an 55

electric fire alarm system, it is to be understood that it is applicable to other uses.

What I claim is:

1. A fusible coupling comprising a relatively thick flat ring-like body of non-conductive, combustible material, said body having a central opening therein and openings through diametrically opposite sides thereof for communication with the central opening, a pair of terminals engaged within the diametrically opposed openings and having reduced inner ends extending into the central opening and spaced from each other, said terminals having longitudinal bores extending into the outer ends thereof for receiving line wires therein, fusible means for sealing said wires within the bores and fusible means in the form of a plug filling the central opening and encasing said reduced ends.

2. A fusible coupling comprising a relatively

thick flat ring-like body of non-conductive, combustible material, said body having a central opening therein and openings through diametrically opposite sides thereof for communication with the central opening, a pair of terminals engaged within the diametrically opposed openings and having reduced inner ends extending into the central opening and spaced from each other, said terminals having longitudinal bores extending into the outer ends thereof for receiving line wires therein, fusible means for sealing said wires within the bores, and fusible means in the form of a plug filling the central opening and encasing said reduced ends, and posts of insulating material secured to and extending at right angles from the body for elevating and spacing the coupling from adjacent surfaces to insulate the same therefrom.

GLEN D. STAUFFER.
